UNITED STATES PATENT OFFICE

ROBERT B. BUZZERD, OF CHARLESTON, WEST VIRGINIA

PHOTOGRAPH-ALBUM PAGE

Application filed July 28, 1928. Serial No. 295,932.

This invention relates to picture collection books and more particularly to pages adapted to carry pictures and intended to be bound together in album or book form.

5 One object of the invention is to provide a collection page which may be sold as a separate article of manufacture so that a person may purchase one or more sheets at a time according to the number of pictures collected 10 at any one time, and these sheets bound in a loose leaf binder.

Another object of the invention is to so form the pages or sheets that, when a number of them are bound together in book or album 15 form, they may be firmly secured but each page allowed to be easily turned.

Another object of the invention is to provide the pages with pockets into which pictures may be easily inserted where they may 20 be viewed through sight openings but prevent the pictures from being liable to easily slip out of their proper positions after being inserted, eliminating the necessity of using an adhesive upon the picture, as adhesives have 25 a tendency to discolor, wrinkle and mar the pictures and the pages upon which they are held.

The invention is illustrated in the accompanying drawings, wherein

30 Figure 1 is a view looking at one face of one of the pages with pictures partially inserted, and

Figure 2 is a longitudinal sectional view taken on the line 2—2 of Fig. 1;

35 Figure 3 is a transverse sectional view taken on the line 3—3 of Fig. 1.

The picture page includes a sheet 1 which may be referred to as a body sheet and is formed of thin cardboard or other relatively 40 stiff material. Facing sheets 2 and 3 are applied to opposed surfaces of the body sheet and have their upper and lower and front edges terminating flush with the edges of the body sheet, whereas their rear end portions 45 project beyond the rear edge of the body

sheet, as shown in Fig. 2. A reinforcing strip 4 is disposed between the extended rear end portions of the facing sheets, and by referring to Fig. 2 it will be seen that the reinforcing strip terminates in spaced relation to the 50 body sheet and between the body sheet and reinforcing strip the facing sheets which are formed of thin paper are pressed together, as shown at 5, and secured by an adhesive. Therefore, the body is formed with a portion 55 6 which may be referred to as a binding portion and through this portion are formed openings 7 to receive fasteners through the medium of which separate pages are to be bound in album form. From an inspection 60 of Fig. 2, it will be readily seen that, when a number of pages are bound together by fasteners passed through the openings 7, the portions 6 will be clamped firmly together but the individual pages may be easily turned. 65 It will be obvious that the facing sheets 2 and 3 may consist of separate sheets of paper or formed from a single sheet folded intermediate its length about the reinforcing strip 4 and secured together, as shown at 5, to provide 70 the hinge portion, after which the body sheet will be set in place between the facing sheets. Openings 8 are formed in the facing sheets and between these openings the facing sheets have adhesive applied so that they 75 may be secured against the body sheet, as shown at 9, and the facing sheets will be adhered to the body sheet adjacent the rear edge thereof, as shown at 10, but the adhesive terminates in spaced relation to the margins of 80 the openings 8 so that, when the photographs 11 are inserted, they will be retained in proper position to be viewed through the openings 8 and it will not be necessary to paste the photographs or pictures in place. At the front 85 end of the page, a portion of the facing sheets are left unsecured to the body sheet, as shown at 12, to provide open spaces or entrances through which pictures may be passed into the pockets adjacent the free forward end of 90

the page, and in order to permit pictures to be inserted in the remaining pockets the upper and lower edges of the facing sheets have portions left unsecured to the body sheet, as shown at 13 in Fig. 3 to define openings or 5 passages through which pictures may be inserted. It should be noted, however, that the entrance 13 at one side of the body opens at the lower edge thereof, whereas the entrance 10 at the other side of the body opens at the upper edge. By this arrangement pictures may be very easily inserted or removed with less likelihood of tearing the unsecured portions of the facing sheets. I have, therefore, 15 provided a picture page having pockets into which pictures may be easily inserted or removed and the pictures will remain in place without being secured by an adhesive. It will also be noted that the pages may be in- 20 dividually purchased as needed.

Having thus described the invention, I claim:

1. A picture collection page comprising a body sheet, facing sheets disposed against opposite faces of said body sheet and formed with openings constituting sight openings, the facing sheets being adhesively secured to the body sheet to define pockets having the openings communicating therewith and certain portions of the facing sheets being free to permit pictures to be passed into the pockets and displayed through the openings, and held in place without the use of any adhesive upon the picture, the facing sheets being extended beyond one side edge of the body sheet and formed with fastener-receiving openings whereby pages may be bound together to form an album, and the pages turned.
- 40 2. A picture collection page comprising a body sheet, facing sheets disposed against opposite faces of said body sheet and formed with openings constituting sight openings, the facing sheets being adhesively secured to the body sheet to define pockets having the openings communicating therewith and certain portions of the facing sheets being free to permit pictures to be passed into the pockets and displayed through the openings, and held in place without the use of any adhesive upon the picture, the facing sheets being extended beyond one side edge of the body sheet, and means carried by the extended portions of the facing sheets to stiffen the 45 same and facilitate binding pages into album form.

- 60 3. A picture collection page comprising a body sheet, facing sheets disposed against opposite faces of said body sheet and formed with openings constituting sight openings, the facing sheets being adhesively secured to the body sheet to define pockets having the openings communicating therewith and certain portions of the facing sheets being free 65 to permit pictures to be passed into the

pockets and displayed through the openings, and held in place without the use of any adhesive upon the picture, the facing sheets being extended beyond one side edge of the body sheet, and a stiffening strip secured between the extended portions of the facing sheets to facilitate binding pages into album form and terminating in spaced relation to the body sheet to permit turning of the pages.

In testimony whereof I affix my signature.

ROBERT B. BUZZERD. [L. S.]
